UNITED STATES PATENT OFFICE.

EDWARD RICHMOND, OF BROOKLINE, MASSACHUSETTS.

IMPROVED LEATHER-PAPER FOR FLOOR-CLOTHS, &c.

Specification forming part of Letters Patent No. 43,340, dated June 28, 1864.

To all whom it may concern:

Be it known that I, EDWARD RICHMOND, of Brookline, in the county of Norfolk and State of Massachusetts, have invented a new and improved method of uniting two or more pieces of leather-paper for making carpets, house-paper, table-covers, crumb-cloths, linings, sheathings, &c., and for painting and embossing the same for the purposes of ornamentation; and I hereby declare that the following is a full, clear, and exact description of my process.

I take ordinary leather scraps and grind or pulp them with vegetable fiber, running out the pulp thus made on an ordinary paper-machine in sheets of various lengths and widths to suit circumstances. I take the paper thus made and scarf or bevel the edges of the same by hand or machinery, so that the extreme edge will be quite thin, and I overlap and connect the two edges thus formed for the purpose together under pressure of clamps, rollers, or in any other convenient manner. The sheets thus united will form one continuous sheet of any desired length or width, which may be printed, stained, or embossed for carpets or floor-cloths, rugs, linings, sheathings, house-paper, table-cloths, and other like articles of manufacture. It will be understood that for car-linings, house-paper, large table-covers, or floor-cloths, made continuous for the whole size of the room or article to be covered, the edges are securely cemented together.

Having thus described my invention, I claim—

As a new article of manufacture, a carpet, rug, lining, table-cover, house or wall paper, made of two or more sheets of leather-paper united at their edges in the manner herein-before described, so as to produce a continuous even-surfaced sheet, substantially as set forth.

In testimony whereof I have signed my name to this specification before two subscribing witnesses.

E. RICHMOND.
